UNITED STATES PATENT OFFICE.

DORSEY F. ASBURY, OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

ENERGY-TRANSLATING DEVICE FOR BREECH MECHANISMS.

1,323,947.

Specification of Letters Patent.

Patented Dec. 2, 1919.

Application filed April 13, 1916. Serial No. 90,891.

To all whom it may concern:

Be it known that I, DORSEY F. ASBURY, a citizen of the United States, residing at Washington, District of Columbia, have invented certain new and useful Improvements in Energy-Translating Devices for Breech Mechanisms; and I do hereby declare the following to be a full, clear, and exact description of the invention, such as 10 will enable others skilled in the art to which it appertains to make and use the same.

My invention relates to energy translating devices for breech mechanisms.

The objects of my invention are to trans- 15 late the energy stored in the carrier while it moves toward closed position to energy to move the plug longitudinally with respect to the carrier as the latter approaches its closed position; to translate the energy 20 of the moving carrier to plug sliding energy; to accelerate the movement of the plug into the breech by the reactionary energy derived from retarding the carrier as the latter approaches the breech; to pro- 25 vide means carried by the mechanism and reacting from the gun to translate the movement of the mechanism toward the breech to increase the velocity of the plug into the breech and thereby arrest the carrier; to 30 use the momentum of the carrier to move the plug longitudinally with respect to the carrier as each move toward the breech; to bring the carrier to rest against the gun without slam by using its momentum to 35 react from the gun to move the plug longitudinally with respect to the carrier; to bring the breech mechanism to rest against the gun without slam by progressively retarding its movement by means operated 40 from the gun and against the plug to move the plug longitudinally with respect to the breech mechanism; to translate the energy stored in the moving breech mechanism to the plug to help rotate the latter; and to 45 retard the breech mechanism by accelerating the movement of the plug longitudinally and then accelerate the rotary movements of the plug by retarding the plug longitudinal movement.

50 In the drawings chosen to illustrate my

invention the scope whereof is pointed out in the claims—

Figure 1 is a horizontal section of a gun embodying my invention, the parts being in the position they would occupy when the 55 breech is being closed and the energy translating devices just beginning to act;

Fig. 2, a view similar to Fig. 1 with the parts in the position they would occupy just as the carrier reaches its closed posi- 60 tion;

Fig. 3, a rear elevation of a gun embodying my invention with the parts in the position shown in Fig. 2;

Fig. 4, a sectional view on the line 4—4 65 of Fig. 2, and

Fig. 5, a section on the line 5—5 of Fig. 3 with the parts in the position shown in Fig. 1.

Referring to the drawings A is the gun, 70 B the breech plug, and C the swinging carrier which latter embodies a spindle C'. The plug B is mounted on the spindle C' for both rotatable and longitudinal movements. Slidable in the bore of the spindle 75 C' is the stem 10 of a mushroom 11 and confined between the plug B and mushroom 11 is a gas check 12.

The plug B is adapted to be rotated by means of a crank shaft 13 operatively connected to a crosshead 14 slidably mounted in a crosshead bearing 14' formed in the breech plug B and rotated through the medium of a handle 15 all as fully described in U. S. Letters Patent 1,020,849 granted 80 to George L. Smith and myself March 19, 1912. It will however be observed that I can employ any suitable means for rotating the plug.

For translating the longitudinal move- 90 ment of the plug relatively to the carrier to rotary movement during closing of the breech and rotary movement of the plug to longitudinal movement during opening of the breech I provide a cam device M which 95 embodies a cam 16 on the carrier and a roller 17 on the plug all constructed, arranged and operated as fully described in my co-pending application filed March 15, 1916 and serially numbered 84348. 100

My present invention particularly embodies a rocking cam 18 mounted on the carrier through the medium of a spindle 19. One end 20 of this cam reacts against 5 the gun and the other end 21 against the plug. The spindle 19 carries a latch arm 22 which coacts with a shoulder 23 on the crosshead bearing 14' to hold the plug against muzzleward longitudinal movement 10 during movement of the carrier not effected by the rocking cam 18.

In closing the breech mechanism the initial operation of the rocking cam 18 occurs when the carrier reaches the position shown 15 in Fig. 1. In this position of the parts the end 20 of the rocking cam enters into initial engagement with a suitable bearing plate 24 fixed on the rear face of the gun. Continued closing movement of the carrier 20 will then rock the cam 18 and the end 21 thereof will act against the plug and move the latter longitudinally with respect to the carrier. During this longitudinal movement of the plug the cam device M will operate 25 to translate the longitudinal movement of the plug to rotary locking movement. In opening the breech the rotary movement imparted to the plug by the operation of the crank shaft 13 will be translated to longitudinal 30 movement of the cam device M. This longitudinal movement of the plug in opening the breech will rock the cam 18 and the end 20 of the latter acting against the plate 24 will initiate the opening swing of the carrier. At the termination of the longitudinal movement of the plug in opening the breech the latch arm 22 will engage against 35 the shoulder 23 and hold the plug B against muzzleward longitudinal movement relative 40 to the carrier during all movements of the carrier that are not effected by the rocking cam 18. It will be noted that in closing the breech the action of the rocking cam 18 serves to retard the movement of the carrier to prevent slamming and at the same 45 time initiates muzzleward longitudinal movement of the plug and accelerates the velocity of such movement. It will be further noted that the rocking cam 18 is so shaped and arranged as to retard the carrier and accelerate the plug in inverse ratio 50 and vice versa.

What is claimed is:—

1. In a breech mechanism for guns, the 55 combination of a movable carrier, a rotatable plug movable longitudinally relative to the carrier, and means operating independently of rotation of the plug during movement of the carrier toward the gun breech to 60 move the plug longitudinally with respect to the carrier.

2. In a movable breech mechanism for guns, the combination of a plug movable longitudinally relative to the other parts of the breech mechanism irrespective of the

plug's other movements, and means operating during movement of the breech mechanism toward the gun to move the plug longitudinally.

3. In a breech mechanism, the combination 70 of a movable carrier, a rotatable and longitudinally movable breech plug, and means operating independently of the rotation of the plug during carrier movement to translate the energy in the carrier to move 75 the plug longitudinally with respect to the carrier.

4. In a breech mechanism, the combination 80 of a movable carrier, a rotatable and longitudinally movable breech plug, and means operating independently of the rotation of the plug during carrier movement to translate the energy stored in the carrier to help move the plug longitudinally with respect to the carrier.

5. In a gun, the combination of a movable breech mechanism including a rotatable plug slidable longitudinally with respect to the other parts of the breech mechanism, and means operating independently of the rotation of the plug during movement of the breech mechanism to initiate sliding movement of the plug with respect to the other parts of the breech mechanism.

6. In a movable breech mechanism for 95 guns, the combination of a plug slidable longitudinally relative to the other parts of the breech mechanism irrespective of the plug's other movements, and means operating during movement of the breech mechanism to 100 initiate sliding movement of the plug.

7. In a gun, the combination of a breech mechanism, the parts of which are adapted for bodily movement in unison, said mechanism including a plug slidable relative to 105 the other parts of the breech mechanism irrespective of the plug's other movements, and means operating during movement of the breech mechanism to initiate sliding movement of the plug.

8. In a gun, the combination of a movable breech mechanism including a breech plug movable longitudinally irrespective of the plug's other movements relative to the other parts of the breech mechanism, and a lever 115 on the breech mechanism reacting against the gun and acting against the plug to push the latter longitudinally with respect to the other parts of the breech mechanism during closing movement of the breech mechanism.

9. In a gun, the combination of a movable breech mechanism including a breech plug movable longitudinally with respect to the other parts of the breech mechanism, and a lever pivoted on the breech mechanism reacting against the gun and acting directly against the plug to push the plug forward with respect to the other parts of the breech mechanism during closing movement of the breech mechanism.

10. In a gun, the combination of a movable breech mechanism including a breech plug movable longitudinally with respect to the other parts of the breech mechanism irrespective of the plug's other movements, and a lever reacting against the gun and acting directly against the plug to push the plug forward with respect to the other parts of the breech mechanism during closing movement of the breech mechanism. 50
11. In a gun, the combination of a movable breech mechanism including a rotatable plug movable longitudinally irrespective of the plug's other movements relative to the other parts of the breech mechanism, and a lever reacting from the gun to push the plug longitudinally with respect to the other parts of the breech mechanism during movement of the breech mechanism. 15
12. In a gun, the combination of a movable breech mechanism including a rotatable plug movable longitudinally irrespective of the plug's other movements relatively to the other parts of the breech mechanism, and a lever reacting from the gun and acting directly against the plug to move the latter longitudinally with respect to the other parts of the breech mechanism during movement of the breech mechanism. 25
13. In a gun, the combination of a movable breech mechanism including a plug movable variably longitudinally with respect to the mechanism, and means reacting from an element fixed relatively to the gun and acted on by the plug during longitudinal movement of the latter to move the breech mechanism relatively to the gun. 35
14. In a gun, the combination of a movable breech mechanism including a plug movable longitudinally with respect to the mechanism, and means reacting from an element fixed relatively to the gun and acted on by the longitudinal movement of the plug to move the breech mechanism relatively to the gun. 40
15. In a gun, the combination of a movable breech mechanism including a rotatable plug movable longitudinally with respect to the other parts of the mechanism and means for translating the energy of the moving breech mechanism to accelerate the movement of the plug toward the gun. 50
16. In a gun, the combination of a movable breech mechanism including a rotatable and longitudinally movable plug, means for translating the energy of the rotating plug to move the plug longitudinally, and a second means for translating the energy due to longitudinal movement of the plug to energy 55 to move the breech mechanism. 60
17. In a gun, the combination of a hinged carrier, a rotatable breech plug mounted on the carrier for movement longitudinally with respect to the latter, and means acting independently of the rotation of the plug 65
- for translating the energy of the swinging carrier to the plug to move the latter longitudinally toward the gun and with respect to the carrier. 70
18. In a gun, the combination of a movable breech mechanism including a breech plug movable longitudinally relative to the other parts of the breech mechanism irrespective of the plug's other movements, and means for translating the energy of the moving breech mechanism to the plug to move the latter longitudinally toward the gun and with respect to the other parts of the breech mechanism. 75
19. In a gun, the combination of a hinged carrier, a breech plug mounted on the carrier for longitudinal movement, and means for translating the energy due to longitudinal movement of the plug to carrier swinging energy. 80
20. In a gun, the combination of a movable breech mechanism including a plug movable independently of the breech mechanism in the direction of the breech, and means acting independently of the rotation of the plug for accelerating the independent movement of the plug toward the breech by energy derived by retarding the breech mechanism as it approaches the breech. 85
21. In a gun, the combination of a movable breech mechanism including a plug movable longitudinally with respect to the other parts of the breech mechanism, and means for increasing the velocity of the plug into the breech and serving to arrest the movement of the breech mechanism. 90
22. In a gun, the combination of a movable breech mechanism including a rotatable breech plug mounted for longitudinal movement with respect to the other parts of the breech mechanism, and means acting independently of the rotation of the plug for moving the plug longitudinally during movement of the breech mechanism. 105
23. In a gun, the combination of a movable breech mechanism including a rotatable breech plug movable longitudinally with respect to the other parts of the breech mechanism, and a device on the mechanism acting independently of the rotation of the plug and reacting from the gun to move the plug longitudinally during movement of the breech mechanism toward the gun. 110
24. In a gun, the combination of a movable breech mechanism including a plug movable longitudinally with respect to the other parts of the breech mechanism, and means directly operated by relative rearward movement of the plug to initiate rearward movement of the breech mechanism. 120
25. In a gun, the combination of a movable breech mechanism including a plug movable longitudinally with respect to the other parts of the breech mechanism, and means reacting from the gun and operating 130

during final closing movement of the mechanism to increase the velocity of the plug toward the breech.

26. In a gun, the combination of a breech mechanism including a hinged carrier, a plug movable longitudinally with respect to the carrier, and means acting during closing movement of the carrier to simultaneously retard the latter and increase the velocity of the plug toward the breech.

27. In a gun, the combination of a breech mechanism including a carrier, a plug movable longitudinally with respect to the carrier, and means acting during closing of the carrier to increase the velocity of the plug toward the breech over the velocity of the plug and carrier prior to the action of said means.

28. In a gun, the combination of a movable breech mechanism including a breech plug, and means for increasing the velocity of the plug into the breech with respect to the velocity thereof incident to the normal unitary closing movement of the plug and mechanism.

29. In a gun, the combination of a movable breech mechanism including a plug movable longitudinally with respect to the other parts of the breech mechanism, and means operated by rearward longitudinal movement of the plug to accelerate rearward movement of the breech mechanism.

30. In a gun, the combination of a movable carrier, a plug movable longitudinally with respect to the carrier, and means operated by the rearward longitudinal movement of the plug and acting against the gun to initiate opening movement of the carrier.

40 31. In a gun, the combination of a movable breech mechanism including a rotatable plug movable longitudinally with respect to the other parts of the mechanism, means for translating the energy of the moving breech

mechanism to move the plug longitudinally, and a second means for translating the energy in the longitudinally moving plug to plug rotation energy.

32. In a breech mechanism for guns, the combination of a movable carrier, a longitudinally movable plug, and means operating during movement of the carrier toward the gun breech to move the plug longitudinally with respect to the carrier, said means operating so that successive unit carrier movements produce varying amounts of plug movements.

33. In a gun, the combination of a movable breech mechanism including a plug movable with respect to the other parts of the breech mechanism in a longitudinal direction, and means operated by retarding and arresting the longitudinal movement of the plug with respect to the breech mechanism to initiate and accelerate rearward movement of the breech mechanism.

34. In a breech mechanism, the combination of a movable carrier, a plug movable longitudinally with respect to the carrier, means for retarding the movement of the carrier, said means acting against the plug to move same longitudinally with respect to the carrier, and a second means acting to rotate the plug while it is moved longitudinally during retardation of the carrier.

35. In a gun, the combination of a movable carrier, a plug movable longitudinally with respect to the carrier, and means operated by rearward longitudinal movement of the plug and acting against the gun to initiate and accelerate the opening movement of the carrier.

In testimony whereof I hereunto affix my signature in the presence of two witnesses.
